[57] **CLAIM**

The ornamental design for a cable car cabin, as shown and described.

DESCRIPTION

FIG. 1 is a top perspective view of a cable car cabin showing my new design;

FIG. 2 is a bottom perspective view thereof;

FIG. 3 is a bottom perspective view from the side opposite that shown in FIG. 2; and

FIG. 4 is a side elevational view thereof.

The side opposite that shown in FIG. 4 is the mirror image of FIG. 4.

FIG. 1

FIG. 2

FIG. 3

FIG. 4
